ATTORNEY

UNITED STATES PATENT OFFICE

WILLIAM GORDON, OF UNION, NEW JERSEY

PEN AND PENCIL CLIP

Application filed February 7, 1929. Serial No. 338,057.

This invention relates to improvements in clips for pens and pencils to secure the same within the pocket of the user.

One of the objects of this invention is to produce a clip preferably pressed into proper position on the pen or pencil by an integral spring and carrying a fabric-engaging spur having independent spring-actuated movement into engagement with the fabric adjustment to the garment pocket upon movement of the clip over the side thereof so as to cause a positive automatic insertion of the spur into the cloth of the pocket upon movement of the pen outwardly without release of said spur and also having means for releasing the spur and preferably sheathing the same to permit withdrawal of the pen or pencil from the pocket.

Still another object of the invention is to provide on a clip a spring-actuated fabric-engaging spur inclining upwardly and normally pressed toward the pen or pencil to which it is attached, combined with release means for said spur adapted to move the same outwardly and away from the fabric to enable withdrawal of the pen.

Still another object of the invention is to provide in a clip having a spring-actuated spur, a releasing element operable by the finger of the user to move the spur against the action of the spring from fabric-engaging to releasing position.

Still another object of the invention is to produce a device of the character described in which the spur is mounted for longitudinal as well as transverse movement and to provide spring means for automatically pressing the spur longitudinally into operative position, combined with release means preferably including a sheath or shield for the spur and a manually-operable release element for moving said spur longitudinally against the action of the spring to release the spur and preferably to move the same behind the shield or sheath.

Still another object of the invention is to provide, in a device of the character described, an upwardly-directed spur having spring means for resiliently pressing the spur to move in a direction transverse of the clip,

and spring means for forcing the element longitudinally of the clip, combined with release means having a finger-operating member preferably arranged above and adjacent to the top of the clip for moving said spur longitudinally against the action of one spring and into engagement with a shield to force said spur transversely against the action of another spring to completely release and shield or sheath said spur.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:

Fig. 1 is a front view of a pencil carrying a clip embodying my invention;

Fig. 2 is a side view of the said pencil and clip seated on the edge of a pocket, the clip being shown in longitudinal section;

Fig. 3 is another longitudinal section of the clip on the line 3-3 of Fig. 2;

Fig. 4 is a transverse section of the clip on the line 4-4 of Fig. 3; and

Fig. 5 is a fragmentary section similar to Fig. 2, showing the clip with its spur in released and sheathed or shielded position.

Referring now to these drawings, which illustrate a preferred embodiment of my invention, 1 indicates a pencil having a cap 2 to which my clip body 3 is attached. The clip body 3 may be fastened to the cap 2 in any suitable manner and, as shown, is provided with an attaching flange 3' and a conventional integral spring-head 4 for resiliently forcing the clip toward the periphery of the pencil cap to contact with the edge of a pocket P when the pencil having the clip is seated thereon and also has a ball 6 to facilitate the movement of the clip 3 over the edge of the pocket.

In the preferred form of my invention illustrated, an upwardly-directed spur member 7 is carried by the clip and has an independent spring-pressed movement into resili-

ient contact with the fabric of the edge of the pocket P. In said preferred embodiment of my invention, a spring 9 is employed for resiliently pressing the said spur member 7 transversely into contact with the fabric of the edge of the pocket P, and, as illustrated, the spur member 7 is hinged or pivoted on a head 7' and the spring 9 is arranged to resiliently swing or move said spur about said head.

Obviously when a spur member is so mounted on the inner surface of a clip, movement of the clip over the edge of the pocket to seat the pen or pencil therein will cause the spur to slide or slip over the cloth, but movement of the clip in the opposite direction to remove the pen or pencil will cause the spur to enter the fabric and positively prevent removal until the spur is released.

Release of the spur is preferably accomplished by providing the lower portion of the clip body 3 with a shielding or sheathing casing 5 which may be of any suitable configuration and the upwardly-directed spring-actuated spur member 7 is mounted for limited longitudinal movement, being movable within and extending above the shielding or sheathing casing 5. Said spur is adapted, when extending above the casing 5, in unshielded or unsheathed position, to resiliently press, as aforesaid, against the fabric over which the clip is moved and to enter the fabric unless released, upon an upward movement of the clip and thus to positively prevent an upward movement of the pen or pencil out of a pocket on the edge of which the pen or pencil clip may be seated.

As illustrated, the spur member 7 is normally forced longitudinally in an upward direction by a coiled spring 8 seated in said shielding or sheathing casing 5.

A releasing element 10 engageable by the fingers of the user is provided to move the element 7 against the action of the spiral spring 8 into the shielding or sheathing casing 5 and during said movement to cause engagement of the spur with the shielding or sheathing casing which will cause a transverse movement of said spur against the action of the spring 9 and a complete release or disconnection thereof from the fabric of the pocket. A limiting stop or collar 10^b on the releasing element 10, is engageable with a partition 11 in the clip and prevents excessive upward movement of the spur 7.

It is desirable that the release element for release or sheathing of the spur may be actuated with facility and with this end in view, I provide the release element 10 with an operating part or extension 10' which extends above the clip and may be readily depressed and held in depressed position against the clip body while the pen is being withdrawn from the pocket, and the entire operation may be accomplished with great facility by

one hand of the user. Said release element 10 has a bearing extending, as shown, through an aperture 3' in the spring-head 4 of the clip and also has a bearing in an aperture 11' in the transverse partition 11. As shown, the release element 10 is connected with the cross head 7', the spur member 7 being provided with a knuckle 7^b hinged on the cross head 7', and the spring 9 is wound around the cross head and has a looped middle portion 9' bearing against the rod, and end portions 9^a bearing against the spur member 7. The operating rod 10 is, as shown, provided at its upper end with a ball 10^a.

It will be understood that the integral spring-head 4 will normally, during a seating of the pen on the fabric of a pocket, retain the clip body in contact with the fabric of the pocket and that the spur 7 has an independent resilient movement transversely of the inner surface of the clip body and the said spur also is capable of limited movement up and down longitudinally and parallel with the axis of the pen and that the spring 8 continuously presses the spur in an upward direction toward the open end of the sheathing casing 5 so as to cause the spur to be resiliently projected outwardly above said open end by the spring 9 and also that the operating mechanism moves the spur longitudinally downward against the operation of the spring 8 which causes the spur to be moved by the casing away from the fabric of the pocket and, furthermore, that the releasing mechanism is conveniently located in a position where it may be readily and quickly operated.

In operation, the user merely slides the clip over the edge of the pocket P in the usual manner. During such movement the sharpened portion 7^a of the spur member will, because of its resilient mounting be automatically moved inwardly and will also slide over the surface of the fabric but the point will remain in contact with the outer surface of the pocket and if an attempt is made to move the pencil or pen upwardly in the pocket, the point will enter the fabric and prevent such movement. Obviously, this device will prevent accidental outward movement or unseating of the pen and will also provide a guard against unauthorized removal thereof.

When a user desires to release the pen, the ball 10^a may be engaged and depressed by one finger to move the operating rod 10' downwardly against the action of the spring 8 and into contact with the head-spring 4 of the clip. This movement, as shown in Fig. 5, will move the cross-head and spur downwardly into the casing 5 and the resiliently-mounted spur will, in such downward movement, be engaged by the wall 5' of the casing 5 and forced transversely and inwardly

against the action of the spring 9 into sheathed or shielded position within the casing 5. Such releasing movement will, of course, cause a complete withdrawal of the 5 spur from any possibility of contact with the garment as it results in complete sheathing of the same as shown in Fig. 5. The holding by the user of the operating rod or stem in depressed position will retain the spur in 10 shielded or sheathed position within the casing and below the edge of the wall 5' thereof so that the pen or pencil may be freely withdrawn from the pocket without any catching of the spur in the fabric of the garment.

15 Having described my invention, I claim:—

1. A clip for pens, pencils and the like, embodying, in combination, a clip body having means for attachment to a pen, a spur member mounted on said clip body to have limited 20 upward and downward movements longitudinally of the clip and substantially parallel with the axis of the pen, a casing open at its upper end within which said spur is adapted to move, a relatively heavy spring mounted 25 within said casing for automatically forcing said spur longitudinally upwardly to the open end of the casing, a relatively light spring for automatically and flexibly forcing said spur transversely toward the pen, 30 manually-actuated releasing means for moving said spur downwardly into said casing against the action of said longitudinal-pressing spring to cause a transverse movement of the spur in the opposite direction and a 35 sheathing thereof by the casing.

2. A clip for pens, pencils and the like, embodying, in combination, a spring clip body having means for attachment to a pen and provided with a casing having an opening 40 at the side thereof adjacent to said pen, a pivotal element mounted in said casing to have limited upward and downward movements longitudinally and substantially coinciding with the axis of said casing, a spur member mounted on said pivotal element to swing transversely of said axis of said casing, means for limiting the upward and downward movement of said pivotal element, spring means mounted within said 45 casing for automatically forcing said pivotal element and spur longitudinally in an upward direction, means for automatically forcing said spur to swing pivotally on said pivotal member transversely of the axis of the 50 casing and through said side opening therein, and manually-actuated means for moving said pivotal element and spur downwardly into said casing against the action of said longitudinal-pressing spring to cause 55 a transverse movement of the spur in the opposite direction and a sheathing thereof by the casing.

In witness whereof, I have signed my name to the foregoing specification.

WILLIAM GORDON.
